US00D981981S

(12) **United States Design Patent** (10) **Patent No.:** **US D981,981 S**
(45) **Date of Patent:** **** Mar. 28, 2023**

(54) **MOBILE PHONE**

(71) Applicant: **BEIJING XIAOMI MOBILE SOFTWARE CO., LTD.**, Beijing (CN)

(72) Inventors: **Luqian Zhou**, Beijing (CN); **Haoxia Wu**, Beijing (CN); **Jiasheng Huang**, Beijing (CN); **Xu Wei**, Beijing (CN); **Yin Zhu**, Beijing (CN)

(73) Assignee: **Beijing Xiaomi Mobile Software Co., Ltd.**, Beijing (CN)

(**) Term: **15 Years**

(21) Appl. No.: **35/514,394**

(22) Filed: **Dec. 1, 2021**

(80) **Hague Agreement Data**

Int. Filing Date: **Dec. 1, 2021**

Int. Reg. No.: **DM/217804**

Int. Reg. Date: **Dec. 1, 2021**

Int. Reg. Pub. Date: **Jun. 10, 2022**

(30) **Foreign Application Priority Data**

Jun. 1, 2021 (CN) 202130331908.1

(57) **CLAIM**

The ornamental design for a mobile phone, as shown and described.

DESCRIPTION

1. Mobile Phone
2. Mobile Phone
3. Mobile Phone
4. Mobile Phone
5. Mobile Phone
6. Mobile Phone
7. Mobile Phone
8. Mobile Phone
9. Mobile Phone
10. Mobile Phone
- 1.1 : Front
- 1.2 : Back
- 1.3 : Left
- 1.4 : Right
- 1.5 : Top
- 1.6 : Bottom
- 1.7 : Front perspective
- 1.8 : Back perspective

1 Claim, 8 Drawing Sheets
